ATTACHMENT FOR SERVING RECEPTACLES

Filed Jan. 4, 1927

UNITED STATES PATENT OFFICE

PAUL W. CURTIS, OF DALLAS, TEXAS, ASSIGNOR TO TRAY SERVICE COMPANY, OF
DALLAS, TEXAS, A CORPORATION

ATTACHMENT FOR SERVING RECEPTACLES

Application filed January 4, 1927. Serial No. 158,995.

This invention relates to attachments for serving receptacles, and especially to attachments for holding covers such as napkins above and over the material such as food that may be served in open receptacles such as 5 trays, or that may be used to hold various cards or other coupons bearing thereon a menu of the several items that are served, or in some cases the bill of items and total 10 expense of the meal or other refreshments served.

It is the purpose of my invention here disclosed to provide means attachable directly to the receptacle on which it is used, preferably applied to the rim thereof, if used on a 15 tray, usually by detachable connection, which will readily function as a holder for the cover or for the said card, and may be readily removed therefrom, as by a swinging movement 20 of the cover frame by relative motion between portions thereof, so that the tray or other receptacle with its contents may be quickly uncovered for emptying the same, the holder attachment readily released from one 25 of the receptacle rims to remove articles held therein, and the card or slip detached from the frame, so that the receptacle may be bodily removed from a particular support leaving the other articles with the refreshments 30 served at the location desired.

It is an object of my invention to arrange such attachments so that any one thereof, any two of them, or all of them may be used on the same receptacle at the same time, and 35 that when used together, as will be explained, no one will interfere with either of the others. Since the demand for service trays and supports therefor has become so great in later years, and is now increasing, some authorities 40 have provided regulations for requiring covering of all kinds of refreshments served in the open air, until it reaches the point of consumption, and it is a special object of this improvement to meet such regulations without 45 unduly inconveniencing the guests to be served, and yet fulfilling the object of such regulations to protect food from outside contamination under proper conditions, and without excessively increasing the cost of the 50 products so served.

With these objects in view, I have provided the structure, and devised the arrangements proposed for accomplishing the results enumerated, as described in the accompanying specification, recited in the appended 55 claims, and illustrated in the accompanying drawings, in which—

Figure 1 is a perspective view of a detachable frame for a tray for holding a cover above the latter; 60

Figure 2 is a detail view of one of the corner posts with its connections with adjoining parts shown in section;

Figure 3 is a detail of link members used in the frame, a portion shown in section; 65

Figure 4 is a side elevation of a clip member shown attached to one of the posts of the frame, certain parts being in section;

Figure 5 is a perspective of one member of a clip; 70

Figure 6 is a similar view of another member of the same clip element;

Figure 7 is a vertical sectional view of another form of clip used in the same relation to other parts; 75

Figure 8 is a perspective view of another manner of attachment of a holding frame to a receptacle;

Figure 9 is a further modified form of holder frame; 80

Figure 10 is a horizontal sectional view of the parts comprising the eye connecting the vertical posts of the frame to the horizontal members;

Figure 11 is a vertical sectional view of the 85 post with the eye member thereof being taken on line 11—11 of Fig. 10; and

Figure 12 is a sectional view of the parts taken on the line 12—12 of Fig. 10.

In the drawings is illustrated a receptacle 90 A, shown in dotted lines in Figs. 1, 8, and 9, as a tray provided with an outer rim portion 10 upon which are attached the devices claimed in this application, and in full lines in Figs. 13, 14 and 17, certain portions being shown in section in other views. The said rim has an upper portion or edge curved outwardly and inwardly to form a bead 11, shown very clearly in Figs. 2, 4, and 18. Upon this bead 11 is mounted certain struc- 100

ture which will be described in detail, other improved structure being applied to the inclined wall 12 of the rim, as will be later explained.

Because of the provisions of certain regulations in communities where effort has been made to protect refreshments served in the open air from contamination injurious to health, I have provided a frame 15 for supporting thereon a proper covering for refreshment serving receptacles which, as shown in Figs. 1 to 7, comprises strands 16, 17 and 18 in parallelism and mounted upon corner standards or posts 13, the rear standards 13 having curved loops 14 at their bases connected by an integral strand 19 which is designed to hug the rim underneath the said bead, as shown in Figs. 1 and 2. The forward posts 13 have loops 20 that are more open than 14 thereby providing connecting strand 21 somewhat outside the vertical plane of the bead, as shown in Figs. 1, 4, 8 and 9, there being a finger hold 22 in said strand 21 making convenient the manual lifting of the front portion of the frame 15 when it is desired to do so.

The rear posts 13 have upward loops 23 irregular in outline, as shown in Figs. 1 and 2, the said loops providing a vertically-elongated eye which comprises means for latching certain frame parts in desired position relative to the posts, such as one side 24 of the loop having an internal shoulder 25 facing downwardly to oppose upward movement of the said frame parts connected in said eye. On the other side 26 of the said loop 23 is provided an upwardly facing exterior shoulder 27 to oppose downward movement of such frame parts. The strands 16 and 17 are shown in Fig. 1 connected by end strands 28 having loops or eyes 29 on their rear ends which are adjustably connected in the eyes 23 of the rear standards 13, the rear end 30 of the eye 29 being shown in Fig. 2 as contacting the shoulder 25, and the forward end of the eye designated by numeral 31 shown engaging the outer shoulder 27 whereby the horizontally extending parts 28 are sustained in such position as illustrated until the eye 29 is moved manually out of contact with such shoulders, so that the parts 28 together with the strand 17 carried thereby may be moved downwardly, being no longer locked in the position shown in Figs. 1 and 2.

The strands 17 and 18 are connected at their ends by cross strands 32, the end strands 28 having loops 33 in which the integral parts 32 and 17 are threaded, and the upper ends of the front standards 13 having similar loops 34 enclosing the common parts 32 and 18. It thus results that the posts 13 hold the strands 16 and 18 in proper position, while the shoulered eyes 23 may support the end parts 32 and 28 in the position shown in Fig. 1. By this arrangement of parts, the finger hold 22

may be raised thereby lifting the forward posts 13 carrying with them the forward frame sections including parts 18, 20 and 21, and finally raising the parts 17, and 28 also so that the receptacle upon which the frame is attached will be wholly uncovered, though the parts 14, 16 and 19 may be permitted to remain in their first position, the 17 and 18 with loops 33 swinging on part 17 over rearwardly beyond the rear outline of the frame. If it is desired, the entire frame 15 may be detached from the receptacle by merely lifting the loops 14 and the strand 19 from the rear edge of the receptacle.

In Fig. 8 is shown a somewhat modified form of the cover frame. Here the connecting strand 19 of Fig. 1 is not used, the lower ends of the loops 14 having short extensions 35 directed toward each other which are connected by oblique strands 36 directed toward the opposite lateral edge of the receptacle but following the bottom of the same exteriorly thereto, until the ends 37 thereof meet and are connected to each other and to the hand loop 38 in the forward strand 21, as indicated in Fig. 8.

In Fig. 9 of the drawings is shown another slight modification of the cover frame, in this instance the strands 16 and 18 of the structure in Fig. 1 being wholly omitted, as well as the rear strand 19, the single connecting strand 17 being supported solely by the loops in the ends of the sections 28 and 32.

In Figs. 4, 5 and 6, is shown an attaching device 39 for clamping the edges of a napkin or a menu card to the frame. In these views such device or clip is shown as formed of two parts—a lower or permanent part 40 having an upwardly directed plate end 41 and an upwardly bent portion 42 integral therewith together with an outwardly bent ear 43, the end part 41 being ordinarily welded or soldered to the several posts or standards 13 of the frame. A longer and movable section 44 is provided with an upper curved portion 45, lower inturned portions 46 and intermediate tongue 47 which, when the two sections 40 and 44 are united, is applied to the part 43 which latter resists outward movement of the portion 45 away from the standard. The two parts 40 and 44 are hinged together in the manner shown in Fig. 4. Another form of clip is shown in Fig. 7, in which the spring pressed clip part 48 is pivotally mounted on the ear 49 of the sleeve 50 which is mounted directly upon the standard 13. The pivot structure of this clip is formed of a coiled spring 51 whose end 52 is bent around the plate 53 to resist movement thereof on the pivot.

In Figs. 10, 11 and 12, I have shown a somewhat modified form of eye on the rear standards 13 for locking detachably therein the cross strands 28, this eye 55 having an internal shoulder 56 much like the shoulder 130

25 as shown in Fig. 2, but provided with an external shoulder 57 which is lateral of the plane of the bar 28 and engages the strand 58 of the loop 59 on the end of the bar 28 in this structure. The loop 59 is rather elongated more in this form of lock than in the form shown in Fig. 2. Otherwise, the function and general structure of the two forms are quite similar.

10 The attaching device 39 may readily serve to hold a napkin therein or any card or slip furnishing any information to the guest concerning the refreshments available, their cost, or both.

15 Having described my improvement and its uses, what I claim and desire to secure by Letters Patent, is—

1. Protective attachments adapted to be mounted detachably upon the rims of a tray 20 for use in serving refreshments therein comprising, a skeleton frame device for supporting thereon a flexible protective cover and including vertical standards attachable to said rims, and spring clips mounted on said 25 standards, respectively, for holding the several edges of said cover.

2. Serving devices of the character described for serving refreshments in a tray comprising, a skeleton frame for supporting thereon a protective flexible cover for the contents of the tray and including vertical standards having looped feet for detachably engaging the rims of the tray, and clips mounted on said standards for holding 35 detachably the edges of said cover.

3. Attachments adapted to be mounted upon the rims of a tray for use in serving refreshments therein comprising, a metallic skeleton frame for supporting thereon a protective flexible cover over the contents of the tray and including vertical standards having 40 clamping feet detachably engaging the said rims and cross strands connecting the upper ends of the standards, one of said strands serving as a pivot on which one portion of said frame may be manually swung upward and backward when desired to open the cover and expose the contents of the tray for service, and clips mounted on said standards 45 intermediate their ends for detachably engaging the edges of the cover.

4. Attachments adapted to be mounted upon the rims of a tray for use in serving refreshments therein comprising, a metallic skeleton frame for supporting thereon a protective flexible cover over the contents of the tray and including vertical standards having 55 clamping feet detachably engaging the rims and cross strands connecting the upper ends of the standards, and clips mounted on the vertical standards for holding detachably the edges of the said cover and comprising a hinged element manually movable relative to the other structure thereof for opening or 60 closing the clip.

5. Serving devices of the character described for serving refreshments in a tray comprising, a skeleton frame for supporting thereon a protective flexible cover for the contents of the tray and including vertical 70 standards having feet arranged in pairs, the feet of each pair being connected by integral strands, and looped to detachably engage the rims of the tray

6. Attachments adapted to be mounted 75 upon the rims of a tray for use in serving refreshments therein comprising, a metallic skeleton frame for supporting thereon a protective flexible cover over the contents of the tray and including vertical standards having 80 clamping feet detachably engaging the said rims and cross strands connecting the upper ends of the standards, one of said strands serving as a pivot on which one portion of said frame may be manually swung upward 85 and backward when desired to open the cover and expose the contents of the tray for service.

7. Attachments adapted to be mounted 90 upon the rims of a tray for use in serving refreshments therein comprising, a metallic skeleton frame for supporting thereon a protective flexible cover over the contents of the tray and including vertical standards having 95 clamping feet detachably engaging the said rims adjacent the corners of the tray and also including spaced but parallel strands mounted upon said corner standards, the rear standards having upward loops providing vertically-elongated eyes which have one side 100 thereof comprising an internal shoulder facing downwardly, and the other side of the eye having an upwardly-facing exterior shoulder, and the parallel strands connected at their ends by cross strands having eyes 105 connecting said elongated eyes in such relation that the said downwardly directed shoulder opposes upward movement of the eye and the said exterior shoulders oppose the down movement of the cross strands, so 110 that said frame may be manually swung upward and backward when desired to open the cover and expose the contents of the tray for service.

8. Serving devices of the character described for serving refreshments in a tray comprising, a skeleton frame for supporting thereon a protective flexible cover over the contents of the tray and including vertical standards having looped feet detachably engaging the rims of the tray and cross strands connecting the upper ends of the standards, two of said looped feet being connected by an integral strand.

In witness whereof I have hereunto set my hand this 28th day of December, 1926.

PAUL W. CURTIS.
